UNITED STATES PATENT OFFICE

154,669

DESIGN FOR A CAPSULE CARRIER

Mack R. Fields, Libertyville, Ill., assignor to Abbott Laboratories, North Chicago, Ill., a corporation of Illinois

Application March 11, 1948, Serial No. 145,020

Term of patent 14 years

(Cl. D16—2)

To all whom it may concern:

Be it known that I, Mack R. Fields, a citizen of the United States, residing at Libertyville, in the county of Lake and State of Illinois, have invented a new, original and ornamental Design for a Capsule Carrier, of which the following is a specification, reference being had to the accompanying drawing, forming part thereof:

Figure 1 is a perspective illustration of a capsule carrier embodying my new design, and

Figures 2 and 3 are side and end elevations respectively of said carrier.

The body of the capsule carrier as illustrated is formed of substantially transparent material so that the capsule-receiving recesses are visible from the outside of the carrier. The top and bottom caps are of opaque material.

I claim:

The ornamental design for a capsule carrier, substantially as shown and described.

MACK R. FIELDS.
